CONTROL VALVE FOR RECUPERATOR MECHANISMS

Filed Nov. 27, 1926

Inventor
H. C. Zimmerman

W.H. Roach.

Attorney

UNITED STATES PATENT OFFICE.

HARRY C. ZIMMERMAN, OF WASHINGTON, DISTRICT OF COLUMBIA.

CONTROL VALVE FOR RECUPERATOR MECHANISMS.

Application filed November 27, 1926. Serial No. 151,217.

(GRANTED UNDER THE ACT OF MARCH 3, 1883; 22 STAT. L. 625.)

The invention described herein may be used by the Government, or any of its officers or employees in prosecution of work for the Government, or by any other person 5 in the United States, without payment to me of any royalty thereon, in accordance with the act of March 3, 1883.

This invention relates to control valves for recuperator mechanisms.

10 In recuperator mechanisms of the hydro-pneumatic type, the retarding influence is exercised by means of a liquid which is obliged to pass through an orifice whose size is diminished as the movement proceeds, 15 thereby checking the recoiling mass. The liquid acts through a floating piston to compress a gas whose expansive force is utilized to restore the gun to battery.

Since the recoil stroke may be shortened at 20 the higher elevations without impairing stability of the mount and since it is convenient to reduce the length of recoil in order to avoid the digging of a hole in the ground, 25 control valves operated by elevation of the gun have been introduced into the recuperator mechanism for reducing the size of the throttling orifice.

Because of the pressure maintained in the recuperator mechanism automatic valves are 30 subject to frequent derangement and accordingly it is the object of this invention to provide a positive, simple, and readily accessible manually controlled valve for varying the size of the throttling orifice.

35 With the foregoing and other objects in view, my invention resides in the novel arrangement and combination of parts and in the details of construction hereinafter described and claimed, it being understood 40 that changes in the precise embodiment of the invention herein disclosed may be made within the scope of what is claimed without departing from the spirit of the invention.

A practical embodiment of the invention 45 is illustrated in the accompanying drawings, wherein:

Fig. 1 is a fragmentary view in longitudinal section of a recuperator cylinder provided with a control valve constructed in accordance with the invention;

50 Fig. 2 is a sectional view on the line 2—2 of Fig. 1;

Fig. 3 is a sectional view on the line 3—3 of Fig. 2.

Referring to the drawings by numerals of reference:

The recuperator cylinder 10 contains the floating piston 11 which separates the liquid chamber 12 from the gas chamber 13. The liquid which is forced from the recoil cylinder (not shown) during recoil of the gun passes through openings 14 in a regulator body 15 whence it unseats the valve 16 against the action of the spring 17 one end of which seats on a block 18 secured to the regulator body. The liquid is then free to pass through the throttling orifice 19 in the block and move the floating piston 11 to compress the gas in the chamber 13. As the movement of the piston proceeds the throttling bar 20 of the piston which tapers outwardly at its free end accordingly diminishes the capacity of the orifice 19 thereby checking the recoiling mass.

The block 18 is also provided with a by-pass 21 herein shown adjoining the orifice 19 and adapted to be closed by a valve 22 threaded as at 23 in the block and extending through the recuperator cylinder where it receives a handle 24. Any suitable means 80 for showing the position of the valve may be provided.

In the present application when the valve 22 is open a recoil stroke of 46 inches is obtained while when the valve is closed the recoil stroke is reduced to 30 inches. The present structure lends itself admirably for replacement of the non-variable throttling devices in existing recuperator mechanisms.

I claim:

1. A recuperator including a cylinder, a floating piston within the cylinder provided with a throttling bar, a block within the cylinder provided with a throttling orifice and a by-pass and a valve extending through the cylinder and block for opening or closing the by-pass.

2. A recuperator including a cylinder, a floating piston within the cylinder provided with a throttling bar, a block within the cylinder provided with a throttling orifice, and an auxiliary manually controlled valve mechanism in the block.

HARRY C. ZIMMERMAN.
